CLAIM

The ornamental design for a card for a bottle, as shown and described.

DESCRIPTION

FIG. 1 is a rear view of the card for a bottle showing our new design;

FIG. 2 is a front view thereof;

FIG. 3 is a perspective view thereof;

FIG. 4 is a perspective view of the card for a bottle in use;

FIG. 5 is a side view of FIG. 4; and,

FIG. 6 is a top view of FIG. 5.

(Continued)

The broken line showing a bottle is included for the purpose of illustrating environmental structure and forms no part of the claimed design.

1 Claim, 6 Drawing Sheets
